CLAIM

The ornamental design for a package, as shown and described.

DESCRIPTION

FIG. 1 is a perspective view of the package with a portion of the flaps being unfolded, showing my new design;

FIG. 2 is a top plan view thereof with all the flaps being unfolded;

FIG. 3 is a top plan view thereof with a portion of the flaps being folded;

FIG. 4 is a left side elevational view of FIG. 3;

FIG. 5 is a right side elevational view of FIG. 3;

FIG. 6 is a front elevational view of FIG. 3;

FIG. 7 is a rear elevational view of FIG. 3;

FIG. 8 is a bottom plan view of FIG. 3; and,

FIG. 9 is a perspective view thereof with all the flaps in a folded position.

The broken lines represent fold lines.
